UNITED STATES PATENT OFFICE.

CHARLES EDWARD HAVILAND, OF LIMOGES, FRANCE.

DESIGN FOR A PITCHER OR SIMILAR ARTICLE.

SPECIFICATION forming part of Design No. 32,874, dated June 26, 1900.

Application filed May 31, 1900. Serial No. 18,684. Term of patent 7 years.

To all whom it may concern.

Be it known that I, CHARLES EDWARD HAVILAND, a citizen of the United States, residing at Limoges, in the Republic of France, have invented and produced a new and original Design for a Pitcher or Similar Article, of which the following is a specification, reference being had to the accompanying drawings, forming a part thereof, and in which—

10 Figure 1 is a side elevation of a pitcher bearing and incorporating my design, and Fig. 2 is a horizontal section of same on the dotted line 2 2 of Fig. 1.

The leading features of my design consist 15 of the shape of the body of the pitcher and the ornamental configuration thereon, substantially as shown.

In the drawings, A designates the body of the pitcher, which body has the downwardly 20 and inwardly inclined side surfaces B, ter-

minating at the curved contracted portion C directly above the ornate scroll-base D. At its upper portion said body A possesses the contracted section F, directly below which and at the upper edge of the body proper is 25 the ornamentation comprising the scalloped scroll configurations denoted at G II, as shown. Extending downward from the points intermediate the scalloped sections of the scroll configuration II are the depressed surfaces or grooves I.

What I claim is—

The design for a pitcher or similar article, substantially as shown and described.

Signed at Paris, in the Republic of France, 35 this 17th day of May, A. D. 1900.

CHARLES EDWARD HAVILAND.
